TELEGRAPH SELECTOR MECHANISM

Russell C. Kinsman, Collinsville, and Thorne Perry, Glastonbury, Conn., assignors to Gray Research and Development Company, Inc., a corporation of Connecticut

Application October 17, 1951, Serial No. 251,726

19 Claims. (Cl. 178—33)

1

This invention relates to telegraph selector mechanisms for interpreting a series of timed signal pulses.

Printing telegraph systems, constituting an important application of this invention, have long been subject to serious limitations because of the complex mechanical linkages employed in the construction of their selector mechanisms. Prior art devices for the purpose have required a large number of operating parts and have been excessively slow and bulky, failing to keep pace with the general progress in the field.

It is foremost among the objects of this invention to provide a selector mechanism which is simple and compact, capable of rapid operation, requiring few parts, and permitting ready servicing in the field. These factors have contributed to a very substantial reduction in cost and maintenance as compared with devices previously employed for similar functions.

The telegraph selectors contemplated herein comprise a frame, an electromagnet carried by the frame having a radial, preferably annular, pole and a winding adapted to be energized by an incoming signal, an armature providing an abutment rotatable with a shaft or rotor about a first axis common to said pole and pivoted about a second axis transversely disposed with respect to the first, armature advancing means carried by the frame for intermittently shifting the armature towards the pole, and a driven member movably carried by the frame in a path traversed by the abutment. The abutment may be rotatable relative to the pole of the magnet and with the armature it may be biased away from the pole about the second axis. Where a biasing spring is employed intermittent shifting of the armature towards the pole must overcome the force of such a spring.

The armature advancing means may assume the form of a cam for each driven member carried by the frame, and such a cam or cams may be of annular form. Each driven member may comprise an arm pivotally carried by the frame and latching means may hold each driven member in certain of its adjusted positions until the completion of a cycle whereupon such member may be biased or otherwise restored to an initial or other adjusted position. A suitable latch releasing mechanism may be provided, and may be carried by the shaft or rotor carrying the armature. Each driven member can actuate a switch or other desired instrumentality, depending upon the specific use for which the apparatus is intended.

2

The armature-carrying shaft or rotor may be connected with and disconnected from a driving shaft intermittently, and may be controlled by incoming signals or otherwise.

5 A more complete understanding of the invention will follow from a detailed description of the accompanying drawings wherein:

Fig. 1 is a somewhat diagrammatic fragmentary perspective view of a selector embodying some of the features of the present invention;

10 Figs. 2, 3 and 4 are fragmentary perspective views based on Fig. 1 depicting positions of the elements under various sets of conditions encountered during operation; and

15 Fig. 5 is a fragmentary perspective view, also somewhat diagrammatic, depicting a selector embodying additional features of the invention.

The selector mechanism depicted in Figs. 1 to 4 includes a shaft or rotor 10 to which a ring 12 is secured by means of a key 14 for rotation about the shaft axis. Between a pair of radial lugs 16 formed on the ring there is received a flange 18 of an armature or striker 20 for relative movement about the axis of a pivot pin 22 transversely disposed with respect to the axis of the shaft 10. The armature is provided with a face plate 24 of paramagnetic material secured at right angles to the flange 18, and a spring 26 bearing against the lower portion of the rear 25 surface of the plate 24 biases the armature clockwise about its pivot to its limiting position shown in Fig. 1.

An annular selector electromagnet 28 surrounds the shaft 10 and comprises a support 30 for a winding 32 which is energized through a pair of conductors 34 by the incoming signal pulses. Where the electromagnet is rendered rotatable with the shaft 10, the conductors 34 may assume the form of slip rings and brushes, whereas a fixed electromagnet can employ conventional leads to constitute the conductors 34. It is intended that the force of the electromagnet 28 when energized will be insufficient of itself to overcome the bias imposed on the armature 20, but the force is quite sufficient to hold the armature in an adjacent position against the biasing effect.

In order to present the face plate of the armature to the electromagnet a suitable number of times per revolution of the shaft 10, a fixed cam member 36 is supported coaxially about the shaft and provides the desired number of cam lobes 38 which extend into the path of the armature flange 18. Consequently, as the shaft 10 rotates, 50 the flange 10 sequentially engages the lobes 38

causing the armature to rock counterclockwise about the pivot 22 towards the winding 32. If the winding is energized at such times, the armature will be magnetically held for the duration of the signal pulse and then restored by its biasing spring 26 to the position shown in Fig. 1.

Also fixed with respect to the shaft 10 is a stator frame 40 having a flange 42 surrounding the electromagnet 28 secured to a flange 44 surrounding the shaft 10 by a suitable number of spacing bars 46. The flange 42 carries a group of terminals 48, 50, and 52 constituting the poles of a single pole double throw switch, there being such a group of terminals for each cam lobe 38. For each such group, the flange 44 carries a shaft 54 pivotally supported in a journal 56. The shaft 54 carries a switch lever 58 having a reduced end 60 projecting into the path followed by the flange 18 when it is remote from the face of the electromagnet. A spring 62 is interposed between a pin 64 and the lever 58 biasing the shaft 54 to the position shown in Fig. 1, where the switch contacts 66 carried by the shaft bridge the terminals 48 and 50. When the armature 20 is retained adjacent the electromagnet as depicted in Fig. 2, the armature flange 18 will clear the switch lever 60 and the switch contacts 66 will continue to bridge the terminals 48 and 50. But when the armature 20 assumes its retracted position under the force of the spring 26, its flange 18 will encounter the switch lever 60 as shown in Fig. 3 and move the upper contact 66 from the terminal 50 towards the terminal 52 until the movement is completed as shown in Fig. 4 where the contacts 66 bridge the terminals 48 and 52. The shaft 54 will be retained in this position by a resilient latch 68 providing a detent 70 for engagement with a cam lug 72. At the termination of a cycle, a support 74 for the latch is moved to the right as viewed in Fig. 4, releasing the cam 72 and permitting the spring 62 to restore the shaft and its switch contacts to their initial positions as depicted in Fig. 1.

By the use of a one-revolution clutch in a manner known in the art, rotation of the shaft 10 is initiated by the first pulse of the incoming signal, and is terminated shortly after the last pulse of the signal.

The mechanism depicted in Fig. 5 requires no resetting operation at the end of each revolution to prepare for the reception of a succeeding pulse. The shaft or rotor 80 has secured thereto by means of a pin 82, a clutch driving member 84 which selectively operates through a clutch spring 86 to rotate the clutch driven member 88. A collar 90 is secured to the driven member 88 for rotation therewith. This collar contains a slot 92 to receive a lever 94 which is mounted for oscillation about the axis of a pivot pin 96 journalled in the collar transversely with respect to the axis of the shaft 80. The lever 94 is secured to an armature 98 which is biased in a counterclockwise direction, as viewed in Fig. 5, about the pivot pin 96 by means of a spring 100 interposed between the collar 92 and the lever 94.

The upper edge of the lever 94 provides a pair of projections 102 and 104 spaced by a gap 106, and the rear or left end of the lever as viewed in the drawing is formed with a projection 108. An annular electromagnet 110 surrounds the shaft 80 and includes a magnetic housing 112 having a radial face interrupted by an annular non-magnetic insert 114 adjacent to the path of the armature 98. Where the electromagnet is fixed to the shaft 80, slip rings 116 interconnect

its winding 118 with the supply leads 120. Where the magnet is fixed relative to the shaft, conventional wiring will suffice.

A relatively fixed cam ring 122 is provided with the desired number of lobes 124 for engagement with the rear projection 104 of the lever 94 to rock the armature 98 towards the magnet periodically as the shaft 80 rotates. In the form illustrated, six such lobes are contemplated, one for each character baud and one for a stop baud provided by the signals supplied over the line 120. A fixed frame 126 supports a switch arm 128 for oscillation about a pivot 130 for connecting and disconnecting the terminals 132 and 134. The arm contains opposed notches 136 for the reception of the rounded ends 138 of levers 140 and 142 pivotally carried by a pin 144 supported in the frame 126. The lower ends 146 of the levers 140 and 142 are selectively encountered by the projections 102 and 104 respectively, depending upon the position of the lever 94 which is determined as in the previous case by whether or not the armature 98 is retained adjacent to the electromagnet or retracted therefrom by the biasing spring 100. It will be clear that when the armature is presented to the magnet 110 to sense a signal baud, if the magnet is energized the armature is retained adjacent thereto and the projection 102 will engage the lever 140 (provided the lever is in its lower position) shifting the switch arm 128 to a position closing the "mark" contacts. Where the "mark" contacts were previously closed (the lever 140 being in its upper position out of the path of the projection 102) no shift of the switch arm will occur. In case the winding 118 is not energized when the armature is presented by a lobe 124 of the cam, the projection 104 will traverse a path including the lower position of the lever 142 to cause the switch arm 128 to close the "space" contacts, provided of course that these contacts are not already closed. As will be clear from the foregoing, there are five such switching assemblies disposed radially about the axis of the shaft 80 and secured to the frame 126.

Also supported by the frame in a suitable manner, is a shaft 148 carrying a lever 150 in the path of the rear projection 108 of the armature lever 94. The lever 150 is biased towards the shaft 80 by means of a spring 152 interposed between an arm 154 of the lever and a lug 156 suitably carried by the frame. The arm 154 terminates in a detent 158 adapted to engage stop lugs 160 and 161 of the one-revolution clutch when the projection 108 engages the lever 150. The clutch will become disengaged under such circumstances and remain so until the winding 118 is deenergized following a stop baud, at which time the armature will be retracted by the spring 100 and the lever 150 restored by its biasing spring 152, releasing the lugs 160 and 161.

A so-called range adjustment as is conventionally employed in this art is readily provided by angular adjustment of the otherwise fixed portions of the frame to permit sampling of the optimum portion of the signal baud.

Inasmuch as variations such as have occurred to the present inventors will be suggested to those skilled in the art by the foregoing disclosure, the specific forms of the invention illustrated and described should not be construed in a limiting sense beyond the scope of the appended claims.

We claim:

1. A telegraph selector comprising a frame, an electromagnet carried by said frame, having a

respect to the first, armature advancing means carried by said frame for intermittently shifting said armature towards said pole, a driven member movably carried by said frame in a path traversed by said abutment, and a clutch for selectively connecting said shaft with a driving member.

14. A telegraph selector comprising a frame, an electromagnet carried by said frame having a radial pole and a winding adapted to be energized by an incoming signal, an armature providing an abutment rotatable about a first axis common to said pole and pivoted about a second axis transversely disposed with respect to the first, armature advancing means carried by said frame for intermittently shifting said armature towards said pole, a plurality of driven members movably carried by said frame in a path traversed by said abutment, and latching means for holding said driven members in certain adjusted positions.

15. A telegraph selector comprising a frame, an electromagnet carried by said frame having a radial pole and a winding adapted to be energized by an incoming signal, an armature providing an abutment rotatable about a first axis common to said pole and pivoted about a second axis transversely disposed with respect to the first, armature advancing means carried by said frame for intermittently shifting said armature towards said pole, a driven member movably carried by said frame in a path traversed by said abutment, means biasing said driven member towards one position, and latching means for holding said driven member in another position.

16. A telegraph selector comprising a frame, an electromagnet carried by said frame having a radial pole and a winding adapted to be energized by an incoming signal, a rotor carrying an armature providing an abutment rotatable about a first axis common to said pole and pivoted about a second axis transversely disposed with respect to the first, armature advancing means carried by said frame for intermittently shifting said armature towards said pole, a driven member movably carried by said frame in a path traversed by said abutment, latching means for holding said driven members in one position, and means carried by said rotor for periodically releasing said latching means.

17. A telegraph selector comprising a frame, an electromagnet carried by said frame having

a radial pole and a winding adapted to be energized by an incoming signal, an armature providing an abutment rotatable about a first axis common to said pole and pivoted about a second axis transversely disposed with respect to the first, armature advancing means carried by said frame for intermittently shifting said armature towards said pole, a driven member movably carried by said frame in a path traversed by said abutment, and a switch actuated by said driven member.

18. A telegraph selector comprising a frame, an electromagnet carried by said frame having a radial pole and a winding adapted to be energized by an incoming signal, an armature providing an abutment rotatable about a first axis common to said pole and pivoted about a second axis transversely disposed with respect to the first, armature advancing means carried by said frame for intermittently shifting said armature towards said pole, a plurality of driven members movably carried by said frame in a path traversed by said abutment, and a plurality of switches carried by said frame actuated by said driven members respectively.

19. A telegraph selector comprising a frame, an electromagnet carried by said frame having a radial pole and a winding adapted to be energized by an incoming signal, an armature providing an abutment rotatable about an axis common to said pole and movable towards and away from said pole, armature advancing means carried by said frame for intermittently shifting said armature towards said pole, and a driven member movably carried by said frame in a path traversed by said abutment.
